UNITED STATES PATENT OFFICE.

ARTHUR TREVOR DAWSON AND GEORGE THOMAS BUCKHAM, OF WESTMINSTER, LONDON, ENGLAND, ASSIGNORS TO VICKERS LIMITED, OF WESTMINSTER, ENGLAND.

RECOIL APPARATUS OF ORDNANCE.

Application filed July 9, 1919. Serial No. 309,784.

To all whom it may concern:

Be it known that we, Sir ARTHUR TREVOR DAWSON, knight, and Sir GEORGE THOMAS BUCKHAM, knight, both subjects of the

5 King of Great Britain, residing at Vickers House, Broadway, Westminster, in the county of London, England, have invented certain new and useful Improvements in or Relating to the Recoil Apparatus of Ordnance, of which the following is a specification.

This invention relates to ordnance recoil apparatus particularly to that type in which the recoil or brake cylinder is connected to 15 the gun so as to move therewith during recoil and run-out and the rod of the recoil piston is connected to the gun cradle so that it remains stationary during the recoil and run-out movements of the gun.

20 According to the present invention the recoil piston has a retarding ram which, during the final portion of the run-out movement of the gun, displaces liquid from a chamber formed, for example, in a plug attached to the recoil cylinder and an adjustable valve is employed for varying, as required, the rate of flow of the liquid so displaced. For the purpose of the invention the said plug may be formed with a hole 25 which opens at one end in the chamber of the plug and at the other end at a part of the plug in contact with the liquid in the rear end of the recoil cylinder and the adjustable valve is preferably of the screw-down type and is arranged in a portion of 30 this hole. The said valve is disposed longitudinally within the plug and in order that it may be readily displaced and adjusted within fine limits it is connected to a 35 worm wheel with which meshes a worm carried by a transversely disposed spindle. The portion of the gun cradle contiguous to this spindle may be formed with a slot by which access can be gained to the said spindle for adjusting the valve.

40 In order that the said invention may be clearly understood and readily carried into effect we will describe the same with reference to the accompanying drawings, in 45 which:—

Figure 1 is a sectional plan of the rear portion of recoil apparatus constructed in accordance with our invention.

Figure 2 is a section taken approximately 50 on the line 2—2 of Figure 1, and

Figure 3 is a side elevation viewed from the right, of the rear part of a gun with its cradle and a portion of the carriage in order to show the aforesaid slot in the cradle.

A is the gun and A' is the cradle on which it slides during recoil and run-out. B is a forging formed with three longitudinal cavities B', B², B³ constituting respectively the recoil cylinder, the recuperator cylinder and the air reservoir and connected at its rear end to a lug A^x, Figure 1, on the gun so that the said forging moves with the gun during recoil and run-out. b', b² are the recoil and recuperator pistons disposed in the cylinders B', B² and connected through their rods to the front end of the gun cradle. B⁴ is the aforesaid retarding ram which is connected to the piston b' and b⁴ is a plug attached by screw threads to the forging B in a position in line with the recoil cylinder B', this plug being formed with a chamber b^{4x} in which the retarding ram is disposed when the gun is in its run-out position, this being the condition of the parts shewn in the drawing. The said retarding ram is formed with a tapered flat surface B^{4x} as shewn in Figure 2 and as is well understood. The plug b⁴ is formed with a hole b⁵ which opens at one end into the chamber b^{4x} and at the other end opens into an annular cavity b^{5x} in communication with the liquid in the rear end of the recoil cylinder. C is the aforesaid adjustable valve arranged in a portion of the hole b⁵, this valve being of the screw-down type disposed longitudinally within the plug. It will be observed that the tapered surface B^{4x} on the retarding ram terminates some distance from the rear face of the piston b' so that during the last few inches of the run-out movement the liquid displaced from the chamber b^{4x} can flow to the cylinder only past the valve C. The stem c of this valve has a squared end fitting within a square hole in a sleeve C' the square hole of which also receives the squared spindle c² of a worm wheel C² with which meshes a worm C³ on a transversely arranged spindle c³. The portion of the gun cradle A' contiguous to the worm spindle c³ is formed with a slot a' (see especially Figure 3) through which a suitable operating device can be inserted to engage with the spindle c³, this operating device preferably comprising a key having a square hole adapted to fit over a squared portion 100

at the end of the spindle or alternatively having a squared end fitting in a square hole in the said spindle. The said slot a' is of sufficient length to permit the spindle c^3 to be operated even if the gun does not fully return to its run-out position after firing. It will be observed that in the construction shewn the said spindle projects to the right of the axis of the recoil cylinder and the slot 10 a' in the gun cradle is accordingly formed in the right hand side wall of the cradle so that the valve can be conveniently operated by a member of the gun's crew (such as the range setting or breech opening member) 15 occupying a position at the right hand side of the gun. It is to be noted that the outer part of the spindle c^3 does not project into the slot a' but lies within the side wall of the cradle.

20 What we claim and desire to secure by Letters Patent of the United States is:—

1. In ordnance recoil apparatus, the combination with the recoil cylinder and the recoil piston, of a chamber supplied with liquid, a retarding ram which enters said chamber during the final portion of the run-out movement of the gun to displace liquid from said chamber, a valve which by its adjustment and without necessitating its 25 removal varies as required the rate of flow of the liquid so displaced, and worm gearing for adjusting said valve, the worm of the worm gearing having its spindle extending substantially perpendicular to the axis of the recoil cylinder, whereby the worm gearing may be operated and the valve adjusted by a member standing at the 30 side of the gun out of the path of recoil. 35

2. In ordnance recoil apparatus, the combination with the recoil cylinder, the recoil piston and the gun cradle, of a chamber supplied with liquid, a retarding ram which enters said chamber during the final portion of the run-out movement of the gun to displace liquid from said chamber, a valve capable of adjustment for varying as required the rate of flow of the liquid so displaced, worm gearing comprising a worm arranged transversely of the recoil cylinder, for adjusting said valve and a slot in the gun cradle exposing said worm for purposes of adjustment.

3. In ordnance recoil apparatus, the combination with the recoil cylinder and the recoil piston, of a chamber supplied with liquid, a retarding ram which enters said chamber during the final portion of the run-out movement of the gun to displace liquid from said chamber, a valve which by its adjustment and without necessitating its removal 60 varies as required the rate of flow of the liquid so displaced, worm gearing for adjusting said valve, the worm of the worm gearing having its spindle extending substantially perpendicular to the axis of the recoil cylinder, whereby the worm gearing may be operated and the valve adjusted by a member standing at the side of the gun out of the path of recoil, and a plug attached to the recoil cylinder, this plug being 65 formed with said chamber and carrying said valve and said worm gearing.

In testimony whereof we affix our signatures.

ARTHUR TREVOR DAWSON.
GEORGE THOMAS BUCKHAM.
